UNITED STATES PATENT OFFICE.

FRANK W. GRAY, OF DETROIT, MICHIGAN, ASSIGNOR TO EASTMAN KODAK COMPANY,
OF ROCHESTER, NEW YORK, A CORPORATION OF NEW YORK.

VIGNETTER.

1,169,802.

Specification of Letters Patent.

Patented Feb. 1, 1916.

Application filed October 5, 1914. Serial No. 865,022.

To all whom it may concern:

Be it known that I, FRANK W. GRAY, of Detroit, in the county of Wayne and State of Michigan, have invented certain new and 5 useful Improvements in Vignettters; and I do hereby declare the following to be a full, clear, and exact description of the same, reference being had to the accompanying drawings, forming a part of this specification, 10 and to the reference-numerals marked thereon.

My present invention relates to photography and more particularly to vignettters and it has for its object to provide 15 a simple, cheap and convenient device of this nature that will be light and serviceable and may be attached readily to any convenient part of a camera or camera support.

The improvements are directed toward 20 providing for a universal adjustment of the mask that can be readily effected by the operator practically with the use of only one hand.

To these and other ends the invention resides 25 in certain improvements and combinations of parts all as will be hereinafter more fully described, the novel features being pointed out in the claim at the end of the specification.

30 In the drawings: Figure 1 is a side elevation of a camera to which has been applied a vignettter constructed in accordance with and illustrating one embodiment of my invention; Fig. 2 is a top plan view thereof; Fig. 3 is a front view of the mask and its immediate support; Fig. 4 is a detail section through the supporting clamp taken on the line 4^x—4^x of Fig. 1; Fig. 5 is a detail section through the clamping nut taken on 35 the line 5^x—5^x of Fig. 1; Fig. 6 is a detail section through the mask holding clip taken on the line 6^x—6^x of Fig. 3, and Fig. 7 is a perspective view partly in section of the mask holding clip.

40 45 Similar reference numerals throughout the several figures indicate the same parts.

Referring more particularly to the drawings, 1 indicates an attaching clamp that is shown applied to the bed 2 of a camera.

50 The clamp may consist of the usual yoke and thumb screw 3, but it carries on its connecting portion 4 a rigid headed stud 5 that forms a pivot for a supporting rod 6 having an eye 7 at its end encircling the stud beneath the head 8 thereof. The spring plate 9

also carried on the stud and prevented from rotation by centering projections 10 engaging notches therein, thrusts the eye 7 against the head 8 and creates a frictional contact by virtue of which the supporting rod will 60 be maintained at any position to which it is adjusted in a vertical plane.

Extending transversely of the supporting rod 6 is a mask holding rod 11 and the respective rods occupy right angle communicating channels 12 and 13 in a clamp nut 14 arranged at their junction so that the rods are in contact with each other. A set screw 15 co-operating with the nut is adapted to engage one and clamp it against the other, 70 as shown in Fig. 5. Both the rods and the channels they occupy are circular so that the former are rotatably adjustable as well as 75 slide longitudinally when the set screw is loosened.

The rod 11 has an eye 16 at its outer end which encircles as a pivot a rigid stud 17 on one of the plates 18 of a spring clip for the usual serrated mask 19. The other plate 20 of the clip which is centered in the superposed relationship by suitable lugs 21 occupying notches in the opposite edges of plate 18, is formed with cutaway portions 22 that give outline to an integral embossed spring washer 23 located within the body of 80 the plate and preferably slotted as at 24 to give greater resiliency. The beforementioned stud 17 extends through the washer 23 and the eye 16 is confined between the latter and the head 25 of the stud so that the washer presses against the eye and offers a frictional resistance to the rotation of the rod 11 on its pivot, or rather, to the rotation of the clip 18—20 upon the rod. It 85 therefore maintains itself readily in any position of adjustment to which it is moved.

The general operation of such a device is well understood in the art and needs no explanation here. Turning the rod 6 on its pivot 5 raises and lowers the mask 19 as does the rotation of the rod 11 and nut 14 upon the rod 6. The mask may be further rotated laterally in its same plane on the pivot 17 of the clip and may be tilted to the front or rear by rotating the rod 11 in the nut 14 while sliding the nut on the rod 6 carries the mask forwardly or rearwardly 90 along the axis of the lens.

It will therefore be seen that a positively 100 universal movement is allowed the mask and 105 110

it is further pointed out that while the operator is using one hand to focus the camera, he can, by grasping only the set screw 15 with the other hand, move the mask to most any desired position of adjustment with the single exception of rotating it on the clip pivot 17. Because of the spring-friction pivots, it will remain in the position to which he moves it as he imparts a final twist 10 to the set screw 15.

The device is composed largely of stampings and can be produced and assembled very cheaply.

I claim as my invention:

15. In a photographic vignetter, the combination with a clamping nut, of a supporting

rod and a relatively transverse mask holding rod slidably and rotatably confined by the nut, a set screw coöperating with the nut to simultaneously secure both rods in their respective adjusted positions, an attaching clamp connected to the supporting rod by a friction-spring pivot and a mask clip connected to the other rod by a friction-spring pivot whereby a complete universal movement may be given the mask by manipulating the set screw. 20 25

FRANK W. GRAY.
